UNITED STATES PATENT OFFICE.

LEE L. TURNER, OF EVANSVILLE, INDIANA.

INTERNAL-COMBUSTION ENGINE.

1,887,417.

Specification of Letters Patent. Patented Apr. 20, 1920.

Application filed February 21, 1919. Serial No. 278,420.

To all whom it may concern:

Be it known that I, LEE L. TURNER, a citizen of the United States, residing at Evansville, in the county of Vanderburgh and State of Indiana, have invented a certain new and useful Improvement in Internal-Combustion Engines, of which the following is a full, clear, concise, and exact description, reference being had to the accompanying drawings, forming a part of this specification.

My invention relates to internal combustion engines, and has for its primary object the provision of a cheap, compact and efficient engine. Although the several improvements of my invention hereinafter pointed out in detail are applicable to engines of various sizes, they possess certain additional advantages when used in connection with engines having relatively low horse power, and for this reason I have described and illustrated the invention as applied to an engine having a horse power of one and one-half.

More specifically my invention relates to that part of the engine which comprises the crank case, the crank shaft, fly wheel and gear and cam mechanism for operating the valve or ignition mechanism, or both.

The outstanding feature of the invention resides in the fact that all of the gear and fly wheel mechanism is entirely inclosed by a single crank case, and that the parts are constructed and arranged so that the process of manufacturing the parts and the method of assembling those parts become very simple, thus reducing the cost of the engine to a minimum.

Notwithstanding the cheapness of construction and compactness of the engine built in accordance with the principles of my invention, the engine possesses certain mechanical advantages over the common type of engine, and these I will point out in detail in connection with the accompanying drawings, wherein—

Figure 1 shows a fragmentary cross sectional view of a gasoline engine provided with the construction of my invention;

Fig. 2 is a detail cross sectional view taken along the line 2—2 of Fig. 1, looking in the direction indicated by the arrows; and

Fig. 3 is a detail view partly in elevation and partly in section, showing the method of connecting the crankshaft with the fly

wheel, this view being taken along the line 3—3 of Fig. 2, looking in the direction indicated by the arrows.

Similar characters of reference refer to similar parts throughout the several views. 60

Referring first to Fig. 1, 4 designates an engine cylinder comprising the bore 5 and the cooling chamber 6. Arranged to reciprocate within the bore 5 in the usual manner is a piston 7 provided with a wrist pin 8, which affords connection between the piston and the connecting rod 9.

Bolted or otherwise secured to the cylinder casing 4 of the engine is a crank case 10, which serves to support the crank shaft 70 and to inclose the fly wheel and gear mechanism, as will be pointed out hereinafter. The crank case 10 includes a cover plate 11, which may be bolted to the crank case or secured thereto in any other convenient 75 manner.

Supported by the crank case 10 and the cover plate 11 which forms a part of the crank casing are the two bearing bushings 12 and 13, forming bearings for the crank 80 shaft 14. This crank shaft is provided with the usual crank arm, shown at 15—15, and a crank pin 15', to which the lower end of the connecting rod 9 is attached. The fly wheel 17 of the engine is positioned as best known 85 in Fig. 1, inside of the crank casing 10, and immediately adjacent one of the crank arms 15. In the preferred form of my invention this crank arm is embedded in the fly wheel, as most clearly shown in Fig. 1. The fly 90 wheel 17 has a driving fit with the crank shaft 14, and is cast so as to provide the recess shown at 16. The particular conformation of this recess is best illustrated in Fig. 2, which shows the recess enlarged at 17 to 95 provide space for the screw and lock nut shown at 18 and 19 respectively. The screw 18 has threaded engagement with the crank arm 15 (Fig. 3) and is adapted to be locked in position by the lock nut 19. The construction just described takes the place of 100 the key and slot mechanism commonly employed for connecting the fly wheel with the crank shaft. It will be observed that by means of the screw and locking nut 18 and 19 the fly wheel may be locked to the crank 105 shaft, more easily than is the case with the old key and slot arrangement. Moreover, after the crank shaft and fly wheel have been connected in this manner, there is abso-

lutely no chance for lost motion between the crank shaft and fly wheel, as was the case in the old arrangement of key and slot.

In locking the crank shaft to the fly wheel, as pointed out above, it is only necessary that the side of the crank arm 15 opposite the screw and locking nut 18 and 19 rest against the wall of the recess 16, but in order to add an additional locking means, 10 the arrangement shown in Figs. 2 and 3 may be employed. This arrangement consists in providing a notch 20 in the wall of the recess 16, into which notch fits the projection 21 of the crank arm 15. This additional locking arrangement insures against longitudinal movement of the fly wheel, although this is by no means necessary, in that the fly wheel may be held against longitudinal movement by the crank arm 15 and 20 the bearing 12, as shown in Fig. 1.

Disposed within the crank casing 10 and keyed or otherwise secured to the crank shaft 14 is a pinion 22 meshing with the gear 23, mounted on the sleeve 24 forming 25 part of a cam 25. The sleeve 24, as shown, extends through the cover plate 11 and has the cam portion 25 thereof disposed outside of the casing. The cam 25 is adapted to cooperate with the roller 26, mounted on the 30 lower end of the pushrod 27, which in turn is arranged to operate a magneto or valve mechanism or both. Pivoted at 28 and 29 to the gear 23 are two centrifugal arms 30 and 31 adapted, when actuated, to press 35 outwardly against a pin 32, normally held in the position shown by the spring 33. The outer end of the pin 32 is arranged to press against the lever 34, pivoted at 35 to the crank casing. The upper end of the lever 40 34 is adapted to engage a projection 36 carried by the pushrod 27. As the speed of the engine increases, the centrifugal arms 30 and 31 are forced outwardly, with the result that the lever 34 is swung in a clockwise direction to engage the projection 36, with the result that the pushrod 27 is held 45 away from engagement with the cam 25.

From the above it will be observed that all of the gearing is entirely inclosed by 50 the crank casing, as is the fly wheel of the engine, and that the single casing is all that is necessary to effect this entire inclosure.

The arrangement of mounting the fly wheel immediately adjacent the crank arms 15 has 55 an additional advantage in that any twisting tendency on the crank shaft is entirely eliminated.

Having thus described my invention, what I claim as new and desire to secure by Letters Patent of the United States is:

1. An internal combustion engine comprising a crank casing, a crank shaft journaled in the casing, a fly wheel provided

with a recess, a crank arm carried by the shaft and extending into said recess, a screw 65 carried by the crank arm and adapted for engagement with one of the walls of said recess, and a substantially V-shaped projection carried by the crank arm on the side opposite the screw, arranged to register in 70 a similarly shaped notch provided in the wall of the said recess, substantially as set forth.

2. An internal combustion engine comprising a crank casing, a crank shaft journaled in said crank casing, a fly wheel mounted on said shaft and disposed immediately adjacent one of the cheeks of the crank forming a part of said crank shaft, said fly wheel comprising abutment portions 75 lying adjacent opposite edges of said crank cheek and embracing said crank cheek between them, together with an adjustable screw threaded into one edge of said crank cheek, said screw arranged to bear against 80 one of said abutments and to hold the opposite edge of the crank cheek against the other abutment.

3. An internal combustion engine comprising a crank casing, a crank shaft journaled in said casing, a fly wheel, said fly wheel disposed immediately adjacent a cheek of the crank forming a part of said crank shaft, said fly wheel comprising abutment portions lying adjacent opposite edges of 95 the said crank cheek and embracing the crank cheek between them, together with adjustable means acting between one of said abutments and the adjacent edge of the crank cheek arranged to hold the opposite 100 edge of the crank cheek firmly in engagement with the other abutment.

4. An internal combustion engine comprising a crank casing, a crank shaft journaled in said casing, a fly wheel, said fly 105 wheel disposed immediately adjacent a cheek of the crank forming a part of said crank shaft, said fly wheel comprising abutment portions lying adjacent opposite edges of the said crank cheek and embracing the 110 crank cheek between them, together with adjustable means acting between one of said abutments and the adjacent edge of the crank cheek arranged to hold the opposite 115 edge of the crank cheek firmly in engagement with the other abutment, the last mentioned abutment and the last mentioned crank cheek each being provided with co-operating V-shaped notch and V-shaped projection substantially as set forth.

In witness whereof, I hereunto subscribe my name this 14th day of February, 1919.

LEE L. TURNEY.
